UNITED STATES PATENT OFFICE.

OLIVER BEDELL HATHAWAY, OF EDISON, OHIO.

WEATHER-STRIP.

SPECIFICATION forming part of Letters Patent No. 408,346, dated August 6, 1889.

Application filed March 8, 1889. Serial No. 302,476. (No model.)

To all whom it may concern:

Be it known that I, OLIVER BEDELL HATHAWAY, a citizen of the United States, residing at Edison, in the county of Morrow and 5 State of Ohio, have invented new and useful Improvements in Weather-Strips, of which the following is a specification.

My invention relates to improvements in weather-strips; and it consists in certain novel 10 features, hereinafter described and claimed.

In the accompanying drawings, Figure 1 is a perspective view of a portion of a door, showing my improved weather-strip applied thereto. Fig. 2 is a bottom plan view of the same. 15 Fig. 3 is a vertical section.

My improved weather-strip comprises a cap-plate A, which is secured to the outer side of the door and projects outward therefrom, the weather-strip proper B, which is 20 arranged beneath the cap A, and a spring C, which is secured to the door and bears upon the strip B. The strip B is hung loosely on the door by means of staples D, secured to the door and passing through openings in the 25 said strip near the upper edge of the same.

A packing-strip G, of rubber or other suitable material, is arranged over the upper edge of the strip B, to prevent water running off the cap and being blown back over the strip

30 B, so as to run down under the door. The spring C is secured to the door at one end, and its other free end projects beyond the edge of the strip B and bears on the under side of the same. The spring thus holds the 35 said strip normally elevated, as will be readily understood, and, if so desired, another spring may be secured at the opposite end of the strip, so as to aid in raising it. When the door is closed, the free projecting end of the

40 spring strikes against the door-jamb, and is thereby pressed toward the door as the door is closed. The end of the spring being thus pressed toward the door, the pressure exerted by it against the weather-strip B is removed,

45 and the said strip then falls by its own weight, so as to cover the space between the lower edge of the door and the upper side of the door sill or threshold. When the door is opened, the spring will again press against 50 the weather-strip and raise it, as will be readily understood.

In order to accommodate the end of the spring when the door is closed, I form a recess J in the edge of the jamb, and provide the said recess with a metallic wear-strip K, 55 as shown. This wear-strip prevents the wood-work of the door-frame being worn away by the constant contact of the end of the spring thereon.

From the foregoing description it will be 60 seen that I have provided a weather-strip which is composed of few parts, and can therefore be manufactured easily and cheaply, which requires no attention when applied to the door, and which, when the door is closed, 65 will effectually cover the space between the door and the threshold, and thereby prevent the entrance of cold air into the room, and also keep out snow and rain, and thus protect the floor and carpet. 70

The cap secured to the door covers the weather-strip and protects the same against injury, and also prevents the snow and rain from running down the door behind the strip B. Inasmuch as the end of the spring contacts with the door-jamb, and is thereby moved from under the strip, so as to allow the strip to fall by its own weight, I dispense with the use of all complicated tripping devices which have been heretofore found necessary. 75

Having thus described my invention, what I claim, and desire to secure by Letters Patent, is— 80

The combination, with the door, of the strip B, loosely hung on the door, the spring secured at one end to the door and having its other end projecting beyond the edge of the door, the intermediate portion of the spring bearing on the strip B, the packing-strip secured to the door and extending over the upper edge of the strip B, and the cap secured to the door and covering the strip B and the packing-strip, as set forth. 90

In testimony that I claim the foregoing as my own I have hereto affixed my signature in 95 presence of two witnesses.

OLIVER BEDELL HATHAWAY.
